UNITED STATES PATENT OFFICE.

FRANK A. BLOCKI, OF SHEBOYGAN, WISCONSIN.

LIFTER-GUARD FOR LODGED GRAIN.

1,258,740.

Specification of Letters Patent. Patented Mar. 12, 1918.

Application filed January 19, 1917. Serial No. 143,218.

To all whom it may concern:

Be it known that I, FRANK A. BLOCKI, a citizen of the United States, and resident of Sheboygan, in the county of Sheboygan and State of Wisconsin, have invented new and useful Improvements in Lifter-Guards for Lodged Grain, of which the following is a description, reference being had to the accompanying drawings, which are a part of this specification.

The invention relates to attachments for harvesting machines, more particularly for a binder.

The invention is more particularly designed to provide an attachment for a binder, to cause the grain or other growing crop to be moved in proper position for the cutter.

One object of the invention is to provide an attachment which may be readily attached to any well-known type of binder by means of a bolt which secures the attachment and finger-guard to the cutter bar, and one in which the supporting bar may be readily adjusted to finger-guards of various sizes.

A further object of the invention is to provide a lifting bar which is yieldingly mounted on its support so that said bar may readily accommodate itself to different conditions of soil over which the binder runs.

The invention further consists in the several features hereinafter set forth and more particularly defined by claims at the conclusion hereof.

In the drawings:

Figure 1 is a view of the device embodying the invention connected to the finger-guard of the cutting mechanism, parts being broken away and parts being shown in section;

Fig. 2 is a plan view showing the attachments in place.

The drawings show a well-known form of cutting mechanism comprising a longitudinally extending angled frame member 3 to which the finger-guards 4 are connected by bolts 5, the cutter blade being reciprocally mounted on said fingers to co-operate therewith in cutting grain or other material.

The attachment comprises a support and connecting member, a lifting bar 7, and means for yieldingly connecting said bar to said support.

The support consists of a two-part member consisting of parts 8 and 9, and means

for adjusting the position of said parts with respect to each other for connecting the attachment to finger-guards of various lengths. The part 8 consists of a flat bar having an angled end 10 provided with an aperture through which the usual bolt 5 connecting the finger to the cutter frame passes, said bolt thus securing said part with said finger to the frame. The part 9 consists of a flat bar having an angled front end 11 forming an eye 12 and having its rear portion overlapping the front portion of the part 8, said part 9 having an angled bracket 13 secured thereto and provided with an aperture 14 for receiving the pointed end 15 of the finger guard 4.

The means for adjusting the parts 8 and 9 with respect to each other may be of any suitable construction though for this purpose I prefer to arrange said parts in overlapping relation and provide a removable bolt 16 for passing through any one of aligned apertures 17 and 18 in said parts 8 and 9 respectively. By means of this two-part adjustable support I am able to adjust said parts so that the apertured bracket 13 will engage the front end of finger 15 and the rear end of the support be secured to the rear end of the finger 4, even though said fingers vary in length.

The lifting bar 7 consists of a flat metal bar having a pointed dividing end 19, a curved shoe portion 20 and a shank portion 21.

The means for yieldingly connecting the lifting bar to the support comprises a bracket 22 secured to the shank 21 and having depending sides 23 each provided with an aperture through which a pivot bolt 24 passes, the eyed end 11 of the part 9 being pivotally mounted on said bolt between said sides, and resilient means operatively connected to said bar and support.

This resilient means consists of a spring 25 which in the present instance is shown as a flat steel spring riveted at one end to the support part 9 to the rear of the pivotal mounting and bowed over so that its other free end engages the under side of the bracket 22 to normally press the front end of the bar 17 downwardly but permits of its upward yielding movement when it meets with an obstruction, the depending front end 26 of the bracket being adapted to abut against the front end 11 of the part 9 to limit the downward movement of the front

end of the bar 7. It will be understood that any other suitable leaf spring could be employed to yieldingly engage the lifting bar in the manner illustrated.

5 From the foregoing it will be seen that the two-part support is such that it may be readily attached to one of the finger-guards of cutting mechanisms of different constructions and adjusted to extend in the line of 10 travel of the machine, and the parts of this support may be moved with respect to each other to different positions. The lifting bar serves to divide and support the crops, holding the uncut crop away from the cutting 15 mechanism and said bar is yieldingly mounted so as to readily pass over obstructions in the field.

What I claim as my invention is:

1. An attachment of the character described comprising a pair of overlapping bars having apertures therein, a bolt passing through registering apertures in said bars to adjustably secure them together, an apertured bracket carried by one of the bars for 20 receiving the end of the finger guard, a flat lifting bar, a bracket secured to said lifting bar and pivotally connected to the bar carrying the apertured bracket, a leaf spring 25 interposed between said lifting bar bracket

and the bar to which it is connected for 30 yieldingly maintaining the front end of said lifting bar in its lower position, and a stop on the lifting bar bracket engaging the bar to which it is connected for limiting the movement of said lifting bar.

2. The combination, with a finger guard and finger board of a binder, and means for securing said finger guard to said board, of an attachment comprising a pair of flat bars overlapping each other for a portion of 40 their length and having a plurality of apertures therein and a bolt passing through registering apertures to adjustably secure said bars together, one of said bars having an angled end secured to the finger board by 45 said finger guard securing means, the other of said bars having an apertured bracket for receiving the end of the finger guard and an eyed end, a lifting bar, a bracket secured to said lifting bar and having depending 50 sides, a bolt passing through the eyed end of the flat bar and through the depending sides of the lifting bar bracket, and a spring for yieldingly maintaining the lifting bar in its lower position.

55 In testimony whereof, I affix my signature.

FRANK A. BLOCKI.
